UNITED STATES PATENT OFFICE.

ELMER E. MOORE, OF MARTINS FERRY, OHIO, ASSIGNOR OF ONE-HALF TO WILLIAM F. RYAN, OF PITTSBURGH, PENNSYLVANIA.

CURTAIN AND SHADE HOLDING BRACKET.

1,322,811.

Specification of Letters Patent. Patented Nov. 25, 1919.

Application filed June 4, 1919. Serial No. 301,642.

To all whom it may concern:

Be it known that I, ELMER E. Moore, a citizen of the United States, residing at Martins Ferry, in the county of Belmont 5 and State of Ohio, have invented a new and useful Curtain and Shade Holding Bracket, of which the following is a specification.

My invention has for its purpose to provide an improved construction of combined 10 window shade and curtain holding bracket of a simple and inexpensive character, in which the parts are especially designed for being quickly and conveniently adjusted for suspending the curtain pole closely to or 15 some distance from the window and in which the supports for the ends of the shade are self-adjusting to adapt them to window shade rollers of different lengths.

My invention also seeks to provide an 20 appliance of the character stated for conveniently placing the shade roller supports along the brackets to give or take-up, should the shade blind be too short or too long relatively to the applied brackets.

With the above and other objects in view, 25 my combined curtain and shade bracket consists of the peculiar arrangement and combination of the parts explained in the following description, specifically pointed 30 out in the appended claims and illustrated in the accompanying drawings, in which:

Figure 1 is a perspective view of one of 35 my improved curtain and shade holding brackets.

Fig. 2 is a longitudinal section thereof and showing the same as operatively applied to a window casing.

Fig. 3 is a similar view of an opposing 40 bracket member as applied to a window casing.

Fig. 4 is a detail cross section of one of the brackets taken on the line 4—4 on Fig. 2.

In the practical application of my invention, the main bracket 1, preferably of strap metal bent to shape, is of substantially triangular shape and the upper and horizontal member 2 thereof has a series of apertures 3, the purpose of which will presently appear.

The inner end of the member 2 and the lower end of the diagonally inclined member 4 of the said bracket terminate in angled foot portions 5—5, each apertured to receive

the screws 6, 6 that secure the brackets to 55 the window casing, as shown.

7, 7 designate rods of suitable diameter and the said rods have their outer ends bent up at right angles to provide relatively long vertical standards 8, 8 for receiving the 60 pole supporting brackets 9, 9.

Each of the brackets 9, 9 includes an upper and lower apertured member 10 and 11 for slidably engaging the standards 8, 8, when the parts are assembled for supporting 65 the curtain pole 12, as is clearly shown in Figs. 2 and 3.

The rods 7, 7 have their inner ends bent downwardly at right angles to form hangers 13 adapted for extending down through 70 any one of the apertures 3 in their respectively engaging bracket members 2 and to provide for positively interlocking the rods with the said members 2, the hangers terminate in angled ends 14 that prevent the rods 75 from pulling off the said members 2, as will be clearly understood by reference to Fig. 4.

In assembling the curtain supporting rod, the outer or standard ends thereof are first slipped up through the selected apertures 3, 80 3 and are so manipulated that the rods assume the position shown in Figs. 2 and 3.

The shade holding elements which constitute one of the essential features of my invention, of which there is one for each 85 35 of the oppositely disposed brackets consisting of a strap metal member 15 whose inner and outer ends are bent at right angles upwardly and constitute inner and outer brackets 16, 16 and 17, 17.

The inner brackets 16 of one of the shade holders has the usual slot 18, see Fig. 1, for the reception of the usual square shaped journal of the shade roller, and the inner bracket 16 of the other or opposing shade 90 95 holder has the usual round aperture, see Fig. 3.

Each of the members 15 are secured to the diagonal members 4 of their respective brackets 1, in the manner best shown in 100 Fig. 1, which illustrates a clamp guide 18' whose opposite ends 19, 19 are bent down from the central portion 20 and have apertures for receiving the securing screws 21, 21 adapted for engagement with the selected 105 ones of threaded apertures 22, 22 arranged lengthwise in the member 4.

By attaching the guides 18 to the incline

bracket members 4, a simple and convenient means is provided for adjustably starting the shade holding members 15 along their coincident bracket members 4 to give or take up the lower end of the blind, should it be a little short or too long, since in the practical arrangement of the bracket parts sufficient adjustment of the member 15, up and down, the bracket member 4 is provided for 10 to allow of several inches rise or fall of the bottom of the shade, when adjusting the same.

Each member 15 is longitudinally slidable and is automatically adjustable in the direction of its length, by a coil spring 23, one end of which is secured to the outermost bracket 17 and the other member to the guide 18', through which the rod member 15 slides.

20 25 indicates a guide attached to the horizontal member 2 of the bracket 1, which guide includes a bifurcated vertical portion in which the rod 7 seats and is held from lateral displacement.

25 26 designates the usual four leaf clamp screw which is used in connection with the support 9.

The yieldable adjustment of the members 15 provides a ready adjustment thereof to 30 accommodate shade rollers of different lengths.

From the foregoing description taken in connection with the drawings, the complete construction, the manner in which my 35 bracket may be operatively applied and adjusted and the advantages thereof will be readily apparent.

What I claim is:

1. An appliance for holding curtains and 40 shades comprising a bracket composed of a body having a horizontal portion and an inclined portion, the said horizontal and inclined portions terminating in apertured

feet, and connected at their other end to constitute a sustaining bracket, the inclined 45 portion of said bracket having adjusting apertures, a guide adjustably secured to the said inclined member and a shade support 50 slideable through the said guide and means for holding the said support in position to engage with the end of the shade roller.

2. An appliance for holding curtains and shades comprising a bracket composed of a body having a horizontal portion and an inclined portion, the said horizontal and inclined portions terminating in apertured 55 feet, and connected at their other end to constitute a sustaining bracket, the inclined portion of said bracket having adjusting apertures, a guide adjustably secured to the said 60 inclined member, and a shade support slideable through the said guides, and means for holding the said support in position to engage with the end of the shade roller, the said means comprising a spring. 65

3. An appliance for holding curtains and shades comprising a bracket composed of a body having a horizontal portion and an inclined portion, the said horizontal and inclined portions terminating in apertured 70 feet, and connected at their other end to constitute a sustaining bracket, the inclined portion of said bracket having adjusting apertures, a guide adjustably secured to the said 75 inclined member, and a shade support slideable through the said guides, and means for holding the said support in position to engage with the end of the shade roller, the said means comprising a spring, the said horizontal portion of the bracket having a 80 series of adjustment apertures, and a curtain rod holder mounted on the said horizontal portion and coöperative with the said apertures therein.

ELMER E. MOORE.
